DESIGN FOR A BOX

Lionel Alfred Ekers, Montreal, Quebec, Canada

Application January 12, 1933, Serial No. 46,804

Term of patent 14 years

To all whom it may concern:

Be it known that I, LIONEL ALFRED EKERS, a subject of the King of Great Britain, and resident of the city of Montreal, in the Province of Quebec, in the Dominion of Canada, have invented a new, original, and ornamental Design for a Box, of which the following is the specification, reference being had to the accompanying drawing, forming part thereof.

Figure 1 is a perspective view of the box opened.
Figure 2 is a perspective view of the box closed.

I claim:

The ornamental design for a box as shown.
Signed at Montreal, Canada, this 28th day of November, 1932.

LIONEL ALFRED EKERS.
